ABSTRACT OF THE DISCLOSURE

Electronic timing relays controlling exposure to light of photographic materials wherein linear adjustment of a variable resistance provides substantially logarithmic adjustment of the timed interval.

This invention relates to electronic timing relays and in particular to relays controlling exposure to light of photographic materials.

Electronic timing relays are known in which the time interval is made dependent upon the mains supply voltage, V_m , in such a manner that compensation is provided over a useful range of mains supply voltage for the effect of variations in such supply voltage on the exposure integral of light against time of the photographic material. Thus, if the light intensity, L , provided by a lamp connected to said mains supply, varies in proportion to V_m^n , then the timing relay is designed to provide a time interval proportional to V_m^{-n} , the design of such timing relays is summarised in "Cold Cathode Tube Circuit Design" (Chapman and Hall Ltd., 1964, pp. 118-125), by D. M. Neale.

In the above prior art, adjustment of exposure time is effected by adjustment of a variable resistance, R , through which a capacitor, C , is charged. The circuit arrangement provides a time interval directly proportional to the product CR . Now it is well known that adjustment of photographic exposure integral, E , is best made by logarithmic increments. If adjustment is made by turning a knob through an angle θ the known type of circuit requires that

But

$$\log E \propto \theta$$

$$E \propto C.R$$

∴

$$\theta \propto \log R$$

This means that, for the said known type of timing relay, the variable resistance R should approximate to a logarithmic resistance/rotation law. There are technical difficulties associated with the provision of such a variable resistance with total resistance value and resistance/rotation law each sufficiently precisely determined to permit the use of a previously-prepared scale in co-operation with a knob on the rotative control shaft of the variable resistance.

The present invention provides an electronic timing relay in which linear adjustment of a variable resistance provides substantially logarithmic adjustment of the timed interval.

The present invention provides moreover that the timed interval shall be inversely proportional to the n th power of the supply voltage where n has a positive finite value not exceeding 6.0.

According to the present invention, there is provided an electronic timing relay which comprises a source of unidirectional voltage across which are connected in series a first fixed resistance, a second fixed resistance and

2

a variable third resistance, such that the current flowing through said third resistance is at all times equal to the current flowing through said first resistance, furthermore a capacitor connected on one pole to the junction of said first and second fixed resistances and charged through a fourth resistance, from the voltage developed across said second fixed resistance, relay means made operative when the sum of the voltages developed across the capacitor and the first resistance reaches a predetermined voltage value.

In one particular form of the invention, the unidirectional voltage has a value substantially 1.8 times the said predetermined value, the first fixed resistance has a value substantially 0.78 times the value of the second fixed resistance, the maximum value of the variable resistance is substantially 1.25 times the value of the second fixed resistance and the fourth resistance is greater than 10 times the value of said second resistance.

In another form, the voltage source provides both unidirectional and sinusoidally alternating voltage components, the value of the unidirectional component being equal to half the peak-to-peak value of the alternating component, the unidirectional voltage component having moreover a value substantially 2.8 times said predetermined voltage value, the first fixed resistance has a value substantially 0.39 times the value of the second fixed resistance, the maximum value of the variable resistance is substantially 3.3 times the value of the second fixed resistance and the fourth resistance is greater than 10 times the value of said second resistance.

Apparatus according to the present invention is of particular use in controlling the exposure to light of photographic material. In this art it is known practice to use a photocell to measure the intensity of light to which the photographic material is to be exposed and thereby to determine the required setting of the timing relay. In particular, it is known practice to place a photo-conductive photocell in the path of printing light, to adjust a variable resistance until a Wheatstone bridge circuit is brought to a condition of balance, the photocell and variable resistance being connected as adjacent arms of said bridge circuit the variable resistance being used at its so-adjusted value to charge a capacitor in a timing circuit controlling the time of exposure of the photographic material to said printing light.

In the said particular known practice, the adjusted value of variable resistance is approximately inversely proportional to the intensity of light falling on the photocell. The known practice therefore suffers from the previously-mentioned disadvantages, viz. that the variable resistance should preferably have a logarithmic resistance/rotation law.

This disadvantage is minimised by use of the apparatus of the present invention and therefore in a preferred embodiment of the present invention, a photometer is provided in which substantially equal increments of a variable resistance R_p are required to operate a relay device when logarithmic incremental changes are made in the intensity of light falling on a photoconductive cell. In use, the photocell is placed in the path of printing light, the said variable resistance R_p is adjusted just to operate the relay device, and the so-adjusted variable resistance, or a sympathetically-adjusted resistance, is thereafter used as the variable third resistance, R_3 , in a timing relay circuit of the type specified above.

By "sympathetically-adjusted" it is meant that adjustment of the value of one of said variable resistances produces an equal or proportional change in the value of the other.

It is an advantage of the photometer circuit proposed here that further increments of resistance may be added

3

or subtracted from said variable resistance in order to adjust the combination of photometer and timing relay to suit photographic materials of different sensitivity. Each such increment will produce substantially the same logarithmic change in sensitivity of the photometer circuit.

According to a further form of the invention, therefore, a variable resistance, R_p , and a fixed resistance, R_A , are connected in series across a source of voltage, the voltage developed across R_A is applied to a fixed resistance R_S and a photoconductive photocell, R_C , connected in series, R_p is adjusted until the voltage developed across R_C is brought to a predetermined value, the so-adjusted value of R_p or a sympathetically-adjusted resistance being used as the value of R_3 in a timing relay circuit as described above.

According to a modified further form of the invention a variable resistance, R_p , a fixed resistance, R_A , and a further fixed resistance, R_B , are connected in series across a source of voltage, the voltage developed across R_A is applied to a fixed resistance R_S and a photoconductive photocell, R_C , connected in series, R_p is adjusted until the sum of the voltages developed across R_C and R_B is brought to a predetermined value, the so-adjusted value of R_p or a sympathetically-adjusted resistance being used as the value of R_3 in a timing relay circuit as described above.

In a particular embodiment of said modified further form of the invention the voltage source provides both continuous and sinusoidally alternating voltage components, the value of the continuous component being equal to half the peak-to-peak value of the alternating component, the continuous voltage component having moreover a value substantially 2.8 times said predetermined value, the resistance R_B has a value substantially 0.22 times the value of resistance R_A and the variable resistance R_p has a maximum value substantially 5.4 times the value of R_A .

The following drawings will serve to illustrate the invention by way of example only, in which:

FIGURE 1 is a circuit diagram of a relay circuit according to the invention.

FIGURE 2 is a graph showing that the timed interval varies in a substantially logarithmic relation to the varied resistance up to a certain value of the variable resistance.

FIGURE 3 is a circuit diagram of another relay circuit according to the invention.

FIGURE 4 is a simple photometer circuit diagram.

FIGURE 5 is a graph showing the substantial logarithmic relation between R_p and the light intensity on R_C .

FIGURE 6 is a modified photometer circuit diagram.

FIGURE 7 is a circuit diagram of a combined photometer and timing relay according to the invention.

In FIG. 1, rectified current from the alternating current mains supply flows through rectifier MR1 to charge C_1 to a voltage V_m .

Resistances R_1 , R_2 and R_3 are connected in series across the supply voltage V_m . The voltage developed across R_2 causes current to flow through resistance R_T charging capacitor C_T until the sum of the voltages across R_1 and C_T equals the critical trigger-to-cathode voltage V_T of the cold cathode trigger tube V_1 . It is well known that the time required for the voltage sum to reach this value is proportional to the product of the values of resistance R_T and capacitance C_T . It is also known that said time is substantially proportional to V_m^n if the resistances values R_1 and R_2 are in the proportion given by:

(Equation 1)

$$\frac{R_1}{R_2} = n \cdot e^{\frac{(1-n)}{n}} - 1$$

where $e=2.718$ approx.

It has now been found that when R_3 in FIG. 1 is varied, the said time bears, over a useful range, a logarithmic relation to the value of R_3 in circuit.

4

If, therefore, a timing circuit is required in which the timed interval is proportional to $V_m^{-3.7}$, R_1 is made equal to $0.78R_2$. Curve A in FIG. 2 shows that, with such a relation between R_1 and R_2 and with V_m equal to $1.8V_T$, the timed interval t varies in substantially logarithmic relation to R_3 up to a value of R_3 equal to $1.25R_2$.

FIG. 3 shows an alternative embodiment in which the positions of C_1 and MR1 have been interchanged. In the arrangement shown in FIG. 3 the voltage V_m varies with time in a sinusoidal manner though remaining always of the same polarity. The voltage V_m therefore comprises two components: one a unidirectional voltage and the other an alternating voltage. The presence of an alternating voltage component in the voltage, V_m , requires that in order to provide a timed interval proportional to V_m^{-n} the ratio R_1/R_2 must depart from the value given by Equation 1 above.

Thus if $n=3.7$, the ratio R_1/R_2 should be approximately 0.39 when the circuit configuration of FIG. 3 is used. With a 240 v. R.M.S. alternating voltage mains input to the circuit of FIG. 3, the continuous voltage component V_m is $240\sqrt{2}=349$ v. Using a trigger tube for which $V_T=123$ v., a dependence of timed interval and the value of R_3 in circuit for values of R_3 lying between $1.5R_2$ and $3.3R_2$.

FIG. 4 represents a simple photometer circuit. Across the series combination of R_A and R_p , a voltage V_m produced in the circuit shown in FIG. 3. R_C is a photoconductive photocell which is placed in the path of light to be assessed. R_S is a comparison resistance of the same order of magnitude as the resistance R_C when illuminated. R_A is chosen to be at least an order of magnitude smaller in resistance than R_S . R_p is adjusted until the peak voltage developed across R_C is equal to the critical trigger-to-cathode breakdown voltage, V_T , of trigger tube V_1 . R_X and R_Y are chosen to restrict the anode current of V_1 to a small value and are proportioned so that at the peak value of V_m the anode-to-cathode breakdown voltage of V_1 is not exceeded.

Curve C in FIG. 5 shows that for values of R_p up to $4.0R_A$, the relation between the adjusted value of R_p and light intensity on R_C is substantially logarithmic. Curve C relates to an alternating voltage mains supply of 240 v. R.M.S. and $V_T=123$ v.

FIG. 6 represents a modified form of photometer circuit in which the additional resistance, R_B , provides a reduction in voltage applied to the photocell, R_C . Curve D in FIG. 5 shows that for values of R_p lying between $1.0R_A$ and $5.0R_A$, the relation between adjusted value of R_p and light intensity is substantially logarithmic. Curve D relates to a value of R_B equal to $0.224R_A$, an alternating mains supply voltage of 240 v. R.M.S. and $V_T=123$ v.

FIG. 7 represents the circuit of a combined photometer and timing relay according to the invention. Switches SW1a, SW1b, and SW1c are coupled. When in the position T as drawn, the circuit functions as a timing relay of the type shown in FIG. 3. When the switches are moved to the opposite position (marked P), the circuit functions as a photometer of the type shown in FIG. 6.

Switch SW2 is coupled either to switch SW3 or to switch SW4. In the following description it will be assumed that SW2 is coupled to SW3 and that SW4 is independently adjustable. Clockwise rotation of SW2 successively removes R_{13} and R_{12} from circuit. Clockwise rotation of SW4 successively removes R_{16} and R_{15} from circuit. Clockwise rotation of SW3 successively removes C_2 and C_3 from circuit.

Terminals 1 and 2 are connected to an alternating voltage mains supply. Rectifier MR1 causes a unidirectional voltage to appear across capacitor C_1 . When switch SW1a is moved from position P to position T, therefore, a current flows through relay coil RLA/3 to charge capacitor C_6 . Thus current is sufficient to energise relay

RLA/3, operating contacts *a/1*, *a/2* and *a/3*. Closure of contacts *a/2* allows relay coil RLA/3 to remain energised by current flowing through resistors R₂₃ and R₂₄. Closure of contacts *a/1* allows the timing capacitance, C_T to be discharged through resistance R₁₈.

To initiate a timed interval, the normally-closed push-button switch PB is briefly opened. This interrupts the path of current through R₂₄. Relay coil RLA/3 thus becomes de-energised and relay contacts *a/1*, *a/2* and *a/3* return to the positions indicated. Contacts *a/3* connect the exposing lamp LE to the mains supply. Contacts *a/1* open to allow the timing capacitance, C_T, to be charged through the timing resistance, R_T, from the continuous component of the voltage appearing across R₂. The timing capacitance, C_T, is represented by those capacitors C₂, C₃, C₄, placed in circuit by switch SW3. The timing resistance, R_T, is represented by those resistances, R₁₄, R₁₅, R₁₆, placed in circuit by switch SW4.

When C_T has charged sufficiently, the sum of the voltages appearing across R₁ and C_T will be sufficient to raise the trigger potential of trigger tube V₂ to the critical voltage V_T. Tube V₂ then conducts to energise relay coil RLA/3, operating contacts *a/1*, *a/2* and *a/3* and thereby terminating the timed interval. Contacts *a/3* operate to remove the mains supply from the exposing lamp, LE, and to energise safelight lamp, LS, contacts *a/1* discharge C_T. Contacts *a/2* close to provide a "hold-on" circuit for relay RLA/3 through R₂₄. When R₂₄ is thus placed in shunt with the anode-to-cathode gape of V₂, the anode potential of V₂ falls below the value required to maintain a discharge. The discharge in V₂ is thus extinguished.

The duration of the timed interval is proportional to the value of C_T selected by SW3, and to the value of R_T selected by SW4. It varies logarithmically also with the proportion of resistance RV1 placed in circuit. Furthermore the time interval varies inversely as the *n*th power of the mains supply voltage where *n* is approximately 3.7.

The sum of the resistances R₁₁, R₁₂, R₁₃, left in circuit by switch SW2 represents the resistance referred to as R_S in connection with FIGS. 4 and 6.

In initially adjusting the apparatus, the coupled switches SW2 and SW3 are set to their mid positions, i.e. R₁₁, R₁₂, C₃ and C₄ are in circuit, R₁₃ and C₂ are out of circuit. Using any convenient negative, a range of test prints is made. For each test print a different timed exposure interval is given corresponding to a different combination of settings of SW4 and RV1. The setting producing a satisfactory print is noted and SW4 and RV1 are subsequently left at this setting unless a more sensitive or less sensitive photographic material is to be exposed or unless the exposing lamp, LE, is exchanged for one of different aetinic value.

When the correct settings of SW4 and RV1 have been thus determined, the photocell R_c is placed to receive light forming a critical part of the negative image, e.g. a picture highlight. Switches SW1a, SW1b and SW1c are now set in position P and RV2 is adjusted to bring the photocell circuit to a balanced condition. As the control RV2 accommodates a range of light intensities equal only to 4 to 1, an optical attenuator (not shown) over the photocell may have to be adjusted to pass more or less light to the photocell.

The balanced condition of the photocell circuit is that in which the peak voltage appearing across R_c and R₁₀ together is just equal to V_T the critical trigger-to-cathode potential of V₂. When this is so, V₂ will conduct. Current will then be drawn by the trigger electrode, so charging C₅ in a sense which inhibits triggering on immediately succeeding cycles of the mains supply voltage. As the charge on C₅ leaks away through R₁₇, however, a condition is reached in which V₂ will again conduct. Conduction of V₂ is observable as a glow on the cathode. The balanced condition is thus observed as the condition in

which the cathode glow appears and disappears at a low frequency e.g. once or twice per second. If the value of RV₂ is too low the pulsations of cathode glow will increase in frequency. For very low values of RV₂, the cathode glow may appear on every cycle of the mains supply voltage. If the value of RV₂ is too high, the frequency of cathode glow pulsation will decrease in frequency and in the extreme condition no glow will occur.

Once the initial adjustment of the apparatus has been made as described above, the method of use is as follows:

Switches SW1a, SW1b, SW1c are first set at position P, so extinguishing the safelight lamp LS, and energising the exposing lamp LE. For each negative image to be printed, the photocell is placed to receive light forming the appropriate critical part of the negative image, e.g. the picture highlight. The settings of switch SW2 and variable resistance RV1 are next adjusted until the balanced condition is indicated by slow pulsation of the cathode glow of V₂. Switches SW1a, SW1b, SW1c are moved to position T, so extinguishing the exposing lamp LE and energising safelight lamp LS. Photocell R_c is removed from the negative image plane and the photographic material is placed in position for exposure. Push-button PB is briefly opened and a timed exposure interval is thereby initiated.

It will be appreciated that because it is coupled to switch SW2, switch SW3 provides step-wise adjustment of C_T in proportion to the step-wise adjustment of R_S. Moreover the circuit values are chosen so that the logarithmic relation of the timed interval to adjustment of RV1 is the same as the logarithmic relation of light intensity on R_c to adjusted value of RV1. Thus when SW2 and RV1 are adjusted to provide coarse and fine adjustment of the photocell circuit to provide a balanced condition in respect of a particular light intensity, adjustment of SW3 and RV1 provides the required adjustment of timed interval such that the timed interval is substantially inversely proportional to the measured light intensity.

In FIG. 7 the adjustable link 3, allows resistances R₆ and R₇ to be put in or out of circuit as required to accommodate the apparatus to alternative nominal mains supply voltages.

In FIG. 7, V₂ is shown as a type of cold cathode trigger tube (Ericsson GPE120T) provided with a priming anode and shield anode. Resistance R₂₂ restricts to a small current the discharge between priming anode and cathode, which discharge provides primary ionisation for the trigger-to-cathode discharge. The shield anode is held at a fraction of the main anode potential by resistances R₂₀ and R₂₁. The function of the shield anode is to inhibit breakdown between main anode and cathode when the latter two electrodes are required to support the voltage developed across C₁.

Resistance R₁₉ limits the main anode voltage and current of V₂ when the apparatus is used as a photometer. Resistance R₈ restricts the current flowing through MRI1 when the mains supply voltage is first applied.

I claim as my invention:

1. An apparatus for controlling photographic exposure which is characterized in that it comprises an electronic timing relay which comprises either a source of unidirectional voltage or a source which provides both unidirectional and sinusoidally alternating components across which source are connected in series a first fixed resistance, a second fixed resistance and a variable third resistance, such that the current flowing through said third resistance is at all times equal to the current flowing through said first resistance, furthermore a capacitor connected on one pole to the junction of said first and second fixed resistances and charged through a fourth resistance, from the voltage developed across said second fixed resistance, relay means made operative when the sum of the voltages developed across the capacitor and the first resistance reaches a predetermined voltage value

and a photometer in circuit with said timing relay wherein a variable resistance R_p , and a fixed resistance R_A , are connected in series across a source of voltage, the voltage developed across R_A is applied to a fixed resistance R_S , and a photoconductive photocell R_C , connected in series, R_p is adjusted until the voltage developed across R_C is brought to a predetermined value, the so-adjusted value of R_p being used as the value of the variable third resistance of the electronic timing relay.

2. An apparatus for controlling photographic exposure which is characterized in that it comprises an electronic timing relay which comprises either a source of unidirectional voltage or a source which provides both unidirectional and sinusoidally alternating voltage components across which source are connected in series a first fixed resistance, a second fixed resistance and a variable third resistance, such that the current flowing through said third resistance is at all times equal to the current flowing through said first resistance, a capacitor connected on one pole to the junction of said first and second fixed resistances and charged through a fourth resistance, from the voltage developed across said second fixed resistance, relay means made operative when the sum of the voltages developed across the capacitor and the first resistance reaches a predetermined voltage value and a photometer in circuit with said timing relay wherein a variable resistance R_p , and a fixed resistance R_A , and a further fixed resistance R_B , are connected in series across a source of voltage, the voltage developed across R_A is applied to a fixed resistance R_S and a photoconductive photocell R_C , connected in series, R_p is adjusted until the sum of the voltages developed across R_C and R_B is brought to a predetermined value, the so-adjusted value of R_p being used as the value of the variable resistance of the electronic timing relay.

3. An apparatus for controlling photographic exposure which is characterized in that it comprises an electronic timing relay which comprises either a source of unidirectional voltage or a source which provides both unidirectional and sinusoidally alternating voltage components across which source are connected in series a first fixed resistance, a second fixed resistance and a variable third resistance, such that the current flowing through said

third resistance is at all times equal to the current flowing through said first resistance, furthermore a capacitor connected on one pole to the junction of said first and second fixed resistances and charged through a fourth resistance, from the voltage developed across said second fixed resistance, relay means made operative when the sum of the voltages developed across the capacitor and the first resistance reaches a predetermined voltage value and a photometer in circuit with said timing relay wherein a voltage source provides both unidirectional and sinusoidally alternating voltage components, the value of the unidirectional component being equal to half the peak-to-peak value of the alternating component, the unidirectional voltage component having moreover a value substantially 2.8 times said predetermined value, there being a variable resistance R_p , and a fixed resistance R_A , and a further fixed resistance R_B , which are connected in series across the voltage source, the voltage developed across R_A is applied to a fixed resistance R_S and a photoconductive photocell R_C , connected in series, R_p is adjusted until the sum of the voltage developed across R_C and R_B is brought to a predetermined value of R_p which is used as the value of the variable resistance of the electronic timing relay.

4. An apparatus according to claim 3 wherein in the photometer the resistance R_B has a value substantially 0.22 times the value of resistance R_A and the variable resistance R_p has a maximum value substantially 5.4 times the value of R_A .
